(57) **CLAIM**

The ornamental design for a butter cutter and storage unit, as shown and described.

DESCRIPTION

FIG. 1 is a right rear perspective view of the butter cutter and storage unit design of the present invention;

FIG. 2 is a front left perspective view of the device shown in FIG. 1; and,

FIG. 3 is a front left perspective view of the device shown in FIGS. 1 and 2 in the open position.

The bottom surface of the device is unadorned.

1 Claim, 2 Drawing Sheets

FIG. 1

FIG. 2

FIG. 3
